US00D604725S

(12) **United States Design Patent**
Chen

(10) **Patent No.:** **US D604,725 S**
(45) **Date of Patent:** **** Nov. 24, 2009**

(54) **SIGNAL ADAPTING APPARATUS**

(75) Inventor: **Sung-Chi Chen**, Chung Ho (TW)

(73) Assignee: **Amtran Technology Co., Ltd.**, Taipei County (TW)

(**) Term: **14 Years**

(21) Appl. No.: **29/321,365**

(22) Filed: **Jul. 15, 2008**

(30) **Foreign Application Priority Data**

Jun. 6, 2008 (TW) 97303332

(51) **LOC (9) Cl.** **14-03**

(52) **U.S. Cl.** **D14/240**; D13/184; D14/433

(58) **Field of Classification Search** D14/356, D14/358, 233, 240, 242, 300, 348, 388, 433, D14/155; D13/184, 137.2, 107, 108, 144; 360/69; 379/220.1, 220.14, 25, 93.09, 93.15, 379/156, 900, 338, 329; 381/124; 607/36; 307/10.1; 439/668

See application file for complete search history.

(57) **CLAIM**

The ornamental design for a signal adapting apparatus, as shown and described.

DESCRIPTION

FIG. 1 is a perspective view of a signal adapting apparatus showing our design;

FIG. 2 is another perspective view thereof;

FIG. 3 is a front elevation view thereof;

FIG. 4 is a top plan view thereof;

FIG. 5 is a rear elevation view thereof;

FIG. 6 is a left elevation view thereof;

FIG. 7 is a right elevation view thereof; and,

FIG. 8 is a bottom plan view thereof.

The broken lines are shown in the views for illustrative purposes only and form no part of the claimed design.
